UNITED STATES PATENT OFFICE.

SAMUEL E. OVERTON, OF SOUTH HAVEN, MICHIGAN.

CORNER-POST FOR CABINETS AND OTHER FURNITURE AND THE PROCESS OR METHOD OF MANUFACTURING SAME.

1,211,620.

Specification of Letters Patent.

Patented Jan. 9, 1917.

Application filed January 26, 1916. Serial No. 74,376.

To all whom it may concern:

Be it known that I, SAMUEL E. OVERTON, a citizen of the United States, residing at South Haven, Michigan, have invented certain new and useful Improvements in Corner-Posts for Cabinets and other Furniture and the Processes or Methods of Manufacturing Same, of which the following is a specification.

10 This invention relates to improvements in corner posts for cabinets and the process or method of manufacturing the same.

The objects of the invention are, first, to provide such a corner post or structure with 15 carving in which all the parts of the carving are well defined. Second, to provide such a corner post of simple construction provided with comparatively elaborate carvings. Third, to provide an improved leg structure 20 for such a corner post and to provide an improved process of manufacturing and producing the same.

Further objects and objects relating to details and economies of construction will 25 definitely appear from the detailed description to follow.

I accomplish the objects of my invention by the devices and means described in the following specification.

30 The invention is clearly defined and pointed out in the claims.

A structure constituting a preferred embodiment of my invention with certain modifications is fully illustrated in the accompanying drawing, forming a part of this specification, in which:

Figure I is a perspective view of a music cabinet provided with talking machine, embodying the features of my invention in its 40 corner posts. Fig. II is a detail perspective view of a portion or section of the corner post. Fig. III is a detail perspective view of the roughed-out blank forming a part of the leg. Fig. IV is a detail view of the 45 blank after it has been carved. Fig. V is a detail view of the completed leg at the bottom of the post, showing the blending of the carving with the bottom end of the post to form the finished carved leg. Fig. VI is a detail transverse sectional view taken on a 50 line corresponding to line 6—6 of Fig. III, showing the contour of the joint parts. Fig. VII is a detail sectional view taken on a line corresponding to line 7—7 of Figs. I and 55 V, showing the cross section of the completed leg structure. Fig. VIII is a detail perspective view of the blank for a carved ornament on the body portion of the leg. Fig. IX is a detail perspective view of the blank partially carved. Fig. X shows the 60 complete ornament. Fig. XI is a sectional view taken on a line corresponding to line 11—11 of Fig. VIII, showing the relative contour of the post and the blank for the carved ornament. Fig. XII is a detail sectional view taken on a line corresponding to line 12—12 of Fig. X, showing the contour and the relations of the completed parts.

In the drawings similar numerals of reference refer to similar parts throughout the 65 several views, and the sectional views are taken looking in the direction of the little arrows at the ends of the section lines.

Considering the numbered parts of the drawings, the cabinet 1 is provided with my 70 improved corner posts 2. These corner posts are cut in the form of a straight molding at the outer corner, as indicated, with a carved surface of the required ornamental design for the body of the post. A suitable ornamental carved capital 10 is at the top and the bottom is finished in an appropriate leg 5. The leg is formed by rough sawing a blank 3, as indicated in Fig. III, on which a suitable pattern for the carving is laid out, 75 and the blank is carved to form the outer portion 4 of the leg, as seen in Fig. IV. This is then applied to the bottom of the post 2, the blank having been cut to conform to the molding, as seen in Fig. VI, and 80 the parts thus glued together are completely 85 carved to form the leg 5, as seen in Figs. I and V, the back portions 6 of the leg being carved at the final operation after the outer portion 4 of the leg has been completely 90 carved, as indicated in Fig. IV. This simplifies the production of the leg, enables the workman to produce substantially the complete carved leg without the necessity of 95 handling the entire corner post, which is of considerable weight and awkward to handle, the back portion at 6 being very readily finished without very much manipulation. The 100 carved ornaments, as 9, and the capital ornament 10 are produced in the same way, and I will describe the production of the simpler ornament 9 as characteristic of the two. A blank 7 is rough sawed (see Fig. VIII) and the back is conformed to the curved portion 105 of the post 2, as seen in Fig. XI. This blank 110

is then carved, as seen at 8 in Fig. IX, and then the process is complete, as seen at 9 in Fig. X, and also in the reduced form at 9 in Fig. I. The small ornament or capital is
5 very readily handled by the workman and completed and artistically carved much more quickly than could be done if carved in position on the post, and by conforming the main shaft of the post to a pleasing design in the
10 form of a straight molding, these parts can be applied and a perfect carving is thus secured with the minimum of labor and of very superior finish.

I desire to state that the designs that I
15 have here shown are conventional and that a great variety of designs can be treated in precisely the manner that I have treated the design here illustrated. I desire to claim the structure broadly, as well as the specific
20 form, and also to claim the process or method by which it is produced, in view of the great economy of labor and material.

Having thus described my invention, what I claim as new and desire to secure by Letters Patent is:

1. An ornamental corner post for cabinets, comprising a straight shaft portion 2, with a straight molding formed thereon, ornaments, the backs of which are exactly
30 formed to the molding of said corner post, and the outer portions suitably carved, and a leg, the outer portion of which is made up

of a suitably carved ornamental portion and the rear portion of which is made up of the carved lower portion of the post blended 35 with the carving of the ornament, as specified.

2. An ornamental corner post for cabinets, comprising a straight shaft portion 2, with a straight molding formed thereon, and a leg, 40 the outer portion of which is made up of a suitably carved ornamental portion and the rear portion of which is made up of the carved lower portion of the post blended 45 with the carving of the ornament, as specified.

3. The process of forming a corner post and leg for cabinets consisting in forming a straight molding at the outer portion of said post, conforming a separate outer portion for the leg to the lower end of said post, carving the outer surface of the same, joining it to the said leg, and carving and finishing the inner portion of the completed leg to blend it with the said outer ornamental portion, as specified. 50

In witness whereof, I have hereunto set my hand and seal in the presence of two witnesses.

SAMUEL E. OVERTON. [L. S.]
